United States Patent Office

Des. 182,625
Patented Apr. 22, 1958

182,625

PREMIUM SELECTOR

Carlos V. St. Claire, El Centro, Calif.

Application January 29, 1957, Serial No. 44,646

Term of patent 14 years

(Cl. D80—1)

FIG. 1.

FIG. 2.

I claim:

The ornamental design for a premium selector, as shown and described.
